Attorney

UNITED STATES PATENT OFFICE.

JOHN H. VENHOFF, OF LOUISVILLE, KENTUCKY.

GAME APPARATUS.

Application filed May 16, 1922. Serial No. 561,264.

To all whom it may concern:

Be it known that I, JOHN H. VENHOFF, a citizen of the United States, residing at Louisville, in the county of Jefferson and State of Kentucky, have invented certain new and useful Improvements in Game Apparatus, of which the following is a specification.

This invention relates to game apparatus consisting of a miniature bowling alley and designed for indoor use.

The invention has for its object to provide in a game apparatus of the kind stated a novel and improved surface projectile to take the place of the balls used on an ordinary bowling alley, and also to provide novel and improved means for accurately and rapidly spotting the pins on the pin field.

With the object stated in view, the invention consists in a combination and arrangement of parts to be hereinafter described and claimed, and in order that the same may be better understood, reference is had to the accompanying drawing, wherein:

Figure 1 is a side elevation of the apparatus; Fig. 2 is a plan view; Fig. 3 is a longitudinal section on the line 3—3 of Fig. 2; Fig. 4 is an enlarged longitudinal section of the pin field, illustrating the operation of the spotting device, and Fig. 5 is a perspective view of the surface projectile used in playing the game.

The preferred embodiment of the invention has been disclosed, but it will be understood that various minor changes and modifications in the structural details may be made without a departure from the spirit and scope of the invention as claimed hereinafter.

Referring specifically to the drawing, 10 denotes an alley or runway for a surface projectile 11, the rear end of said alley being a field 12 on which seat pins 13 having the shape of ordinary bowling pins, but much smaller in size as the apparatus is portable and designed for indoor use. The dimensions of the apparatus are such that it can be placed on a table or other suitable elevated support.

The projectile 11 is a substantially conical block as shown in Fig. 5, and it is adapted to be flipped by the player's finger to slide down the alley 10 and knock the

pins 13 down as in an ordinary bowling game. The block is started at a foul line 14 located at the forward end of the alley 10. In operating the block, it is so placed that one of its inclined sides faces in the direction of the pin field 12. In going down the alley the resistance of the air pressing against the inclined surface has a tendency to hold the block down on the alley and prevent it from jumping.

The alley 10 is composed of a strip of wood or other material mounted on a base board 15 which may be made somewhat wider than the strip forming the alley or runway for the projectile 11, and at the longitudinal edges of the base board are upstanding guard rails 16 to prevent the projectile from leaving the base board. Immediately to the rear of the pin field 12, the rails 16 are made higher, as shown at 17, and are connected at their rear extremities 70 by a transverse wall 18. The parts 17 and 18 form the side and end walls of an enclosure located to the rear of the pin field, and serving to receive the pins 13 as they are knocked down by the projectile 11. 80

The base board 15 stops short of the rear edge of the pin field 12 so as to leave the pin field projecting from the rear end of the base board. In the recess thus formed beneath the pin field is located a plate 19 which projects rearwardly from the same far enough to form the floor of the enclosure produced by the walls 17 and 18. In the pin field are vertical apertures 20 extending completely therethrough and adapted to be entered by upstanding pins 21 on the top of the plate 19. The apertures 20 are grouped to correspond to the grouping of the pins 13 when they are properly set up. When the pins 21 are properly seated in the apertures 20, they are flush at the top with the surface of the pin field as shown in Fig. 3, and the pins 13 will be placed on the spots defined by said pins 21. 95

The plate 19 forms a rear continuation of the base board 15, but these parts are separate and movable vertically relative to each other for the purpose of inserting the pins 21 into the apertures 20 and for withdrawing the same. To the side edges of the plate 19 are secured guide strips 22 which extend upwardly to seat alongside the outer faces of the walls 17 and receive outstanding pins 100

105

23 carried by said walls, the strips having vertical slots 24 through which the pins extend.

The base board 15, the alley strip 10, and the walls 16 and 17 are all rigidly connected, and hence when they are lifted, the plate 19 stays down as shown in Fig. 4, causing the pins 21 to be withdrawn from the spotting apertures 21. The same result is attained 10 by slightly lifting up on the walls 17 or 18. The pins 13 are now placed in the apertures 21, the upper ends of the latter being slightly flared so that the pins may enter the same for a short distance as shown in 15 Fig. 4. The pins 13 being now properly spotted, the portion of the apparatus which was raised from the table or other supporting surface is allowed to lower, whereupon the pins 21 re-enter the apertures 20 and 20 push the pins 13 out of the same, the extent of the relative movement of the parts being such that the pins 21 come flush with the surface of the pin field 12, as shown in Fig. 3. Each pin 13 is now seating on the upper 25 end of a pin 21 flush with the surface of the

pin field. The structure therefore greatly facilitates the rapid and accurate setting up of the pins 13.

I claim:

A bowling game apparatus comprising a 30 base having a rear portion, said base and its rear portion being relatively movable in a vertical direction, an alley on the base and having a pin field above the rear portion thereof, said pin field having spotting apertures 35 extending vertically therethrough, upstanding pins on the rear base portion adapted to enter the spotting apertures and to leave the same when the base and its rear portion are moved relative to each 40 other, upstanding guard rails at the side edges of the base and separate from the rear portion thereof, vertically slotted guide strips carried by the rear base portion and positioned alongside the corresponding portion of the guard rails, and pins extending outwardly from said rear portion of the 45 guard rails into the slots of the strips.

In testimony whereof I affix my signature.

JOHN H. VENHOFF.
